FACING BLOCK FOR FLOORSLABS, FACING STONES, BRICKS AND THE LIKE Thomas M. Rago, D-8901 Stadtberger,
Drosselweg 6, Germany

Filed Nov. 1, 1973, Ser. No. 411,807

Claims priority, application Germany May 25, 1973

Term of patent 14 years

Int. Cl. D25—01

U.S. Cl. D25—80

FIG. 1.**FIG. 2.**

FIG. 1 is a top, plan view of a first embodiment of a facing block for floorslabs, facing stones, bricks and the like of the present invention, wherein the fields are all of the same color; while

FIG. 2 is a top plan view of a second embodiment of the facing block for floorslabs, facing stones, bricks and the like of the present invention, wherein the adjacent fields have different colors.

The embodiments illustrated are flat and have a standard, conventional thickness, the bottoms being plain and unornamented.

I claim:

The ornamental design for a facing block for floorslabs, facing stones, bricks and the like, as shown and described.
